UNITED STATES PATENT OFFICE.

JOHANNES LOOSE, OF STUTTGART-CANNSTATT, GERMANY, ASSIGNOR TO THE FIRM OF FORTUNA-WERKE, SPEZIALMASCHINENFABRIK, G. M. B. H., OF STUTTGART-CANNSTATT, GERMANY.

LEATHER-PARING MACHINE.

1,345,941.

Specification of Letters Patent.

Patented July 6, 1920.

Application filed March 27, 1916, Serial No. 87,074. Renewed March 17, 1920. Serial No. 366,689.

To all whom it may concern:

Be it known that I, JOHANNES LOOSE, of 31 Karlstrasse, Stuttgart-Cannstatt, in the Kingdom of Wurtemberg, German Empire, 5 superintendent, have invented certain new and useful Improvements in Leather-Paring Machines, of which the following is a specification.

My invention relates to the working of 10 leather and more especially to improvements in leather paring machines.

For the purpose of grooving leather it has already been suggested to provide the presser foot in leather paring machines with 15 an excrescence which presses the leather against the knife so that it is cut thinner there.

Now in accordance with this invention the improvement consists in forming this 20 excrescence as a separate removable pressure piece instead of having it integral with the presser foot. The improvement constitutes a considerable advance in the art inasmuch as a separate presser foot is now no longer 25 necessary for each groove to be formed, but the same presser foot can be provided with one or more pressure pieces, in such a way that according to requirements one or more grooves of different form can be made. Fur- 30 thermore the distance between the pressure pieces may be varied, so that grooves may be made in the material any desired distance apart.

The invention is illustrated in several 35 forms of construction as an example in the accompanying drawings in which:—

Figure 1 is an elevation of the part in question of a leather paring machine pro- 40 vided with the improvement.

Fig. 2 is a section of another form of construction.

Fig. 3 is a section of a piece of leather which is provided with two grooves, which 45 grooves are made by means of the invention illustrated in Fig. 1.

Fig. 4 is a section on an enlarged scale of another way of fastening the pressure piece.

According to this invention the presser foot *b* is provided with a releasable pressure 50 piece *a*, the lower side of which is made to correspond with the groove to be formed.

As Fig. 1 shows, the presser foot is provided with several releasable pressure pieces *a* by means of which grooves *f*, as shown in Fig. 3 may be formed in the piece of material *g*. 55 The knife is indicated by *d*, while *e* represents the conveyer roller.

In all three forms of construction the pressure piece is adapted to be displaced and fixed. In accordance with the form of construction illustrated in Fig. 1; the pressure pieces *a* are mounted in a slot *h*, and are adapted to be displaced and fixed, while according to Fig. 2 the pressure piece *a* partially incloses the presser foot *b*, and in Fig. 60 4 it incloses it all around. The pressure pieces *a* are fixed by means of screws *c*.

The number, shape, and method of fixing the pressure pieces *a* is of subordinate im- 65 portance, the most essential thing in the present invention being that the pressure pieces may be releasably connected with the presser foot. The material (operated on) is also immaterial; instead of leather any other suitable material may be employed. 75

I claim:—

1. In a machine for paring leather and like material, in combination, a presser foot, and associated with said foot at least two pressure pieces adjustable in such manner 80 as to vary the distance between said pressure pieces.

2. In a machine for paring leather and like material, in combination, a presser foot, and a plurality of detachable pressure pieces 85 associated with said foot, said pressure pieces being adjustable on the pressure face of the presser foot.

3. In a machine for paring leather and like material, in combination, a presser foot 90 and a plurality of detachable pressure pieces associated with said foot, said pressure pieces being adjustable substantially in the direction of extension of the pressure edge 95 of the presser foot.

In testimony whereof I affix my signature in presence of two witnesses.

JOHANNES LOOSE.

In presence of—

FRIDA KLAIBER,
ERNST ENSENMARY.
